HYDRAULIC MACHINE

Arthur Young, York, Pa., assignor to S. Morgan Smith Company, York, Pa., a corporation of Pennsylvania

Application August 3, 1936, Serial No. 94,009

2 Claims. (Cl. 253—122)

This invention relates in general to improvements in hydraulic machines, and relates more specifically to improvements in the construction and operation of wicket gate actuating mechanisms for hydraulic turbines and the like.

An object of the invention is to provide new and useful improvements in the construction of wicket gate actuating mechanisms for hydraulic turbines and the like having what is commonly termed the submerged type of gate operating mechanism with the shifting ring on the curb or bottom plate.

Another object of the invention is to provide a connection between the wicket gates of a hydraulic turbine and the gate shifting ring which may be readily inserted and removed, thereby permitting ready assembling and disassembling of the parts of the turbine.

Another object of the invention is to provide an improved wicket gate link for hydraulic turbines.

Another object of the invention is to provide an improved pin for connecting the links with the wicket gates of a hydraulic turbine.

Another object of the invention is to provide an improved construction of wicket gate actuating mechanism for hydraulic turbines of the character mentioned which is simple in construction, and reliable and exact in function under all conditions of service.

The invention also comprises certain new and useful improvements in the construction, arrangement and combination of the several parts of which it is composed, as will be hereinafter more fully described and claimed.

In the accompanying drawings:

Figure 1 is a vertical section of a hydraulic turbine showing the application of my invention thereto;

Fig. 2 is an enlarged horizontal section taken on the line 2—2 of Fig. 1 showing in plan, a plurality of wicket gates connected to the gate shifting ring by means of my improved gate link, the section lines for the wicket gates being omitted to more clearly show the parts underlying the wicket gates;

Fig. 3 is an enlarged plan, partly in section, of one of the wicket gates and the link which connects the wicket gate with the gate shifting ring, as seen from the line 3—3 of Fig. 4, the manner of removing and inserting the gate link being shown by broken lines;

Fig. 4 is a vertical section taken on the line 4—4 of Fig. 3; and

Fig. 5 is an enlarged perspective of the pin

used to connect one end of the gate link with a wicket gate.

Referring to the drawings, the type of hydraulic turbine to which the invention has been specifically applied by way of illustration comprises a runner 11 mounted in an open flume setting consisting of a bottom or curb plate 12 disposed on a concrete pedestal 13, and a top or crown plate 14 superposed above the bottom or curb plate 12 and supported by a plurality of columns 15, also carried by the pedestal 13, as shown in Fig. 1. The space between the bottom or curb plate 12 and top or crown plate 14 constitutes an annular inlet for the water delivered to the runner 11, and beneath the bottom or curb plate 12 there is the usual draft tube 16, through which the water flows after it leaves the runner. The top or crown plate 14 is so formed as to direct the water towards the runner 11 in the usual manner.

The bottom or curb plate 12, pedestal 13 and top or crown plate 14 are circular in form, and the columns 15, which are spaced a suitable distance apart, are arranged around the peripheries of the top and bottom plates, as shown in Figs. 1 and 2.

Vertically disposed between the bottom or curb plate 12 and the top or crown plate 14, is an annular series of wicket gates 17, which are arranged within the annular series of columns 15. As shown in Fig. 2, the number of wicket gates 17 may exceed the number of columns 15. The wicket gates 17 are adapted to be rotated simultaneously into different angular positions to control the flow of water to the runner 11.

Each wicket gate 17 is pivotally mounted on a shaft 18 which extends through the wicket gate, the lower end of the shaft being journalled in a suitable opening 19 formed in the bottom or curb plate 12 and the upper end of said shaft is journalled in a bushing 20 mounted in the top or crown plate 14. The upper and lower extremities of the shaft 18 are threaded for the reception of nuts 21, 22, respectively, which are adapted to retain the shaft in position.

The wicket gates 17 and shafts 18 are so formed that when the nuts 21, 22 are removed, the shafts can be withdrawn upwardly to permit the dismantling of the wicket gates without interference from the other parts of the turbine setting.

Encircling the periphery of the curb plate 12, is a gate shifting ring 23 which is supported by a suitable flange 24 projecting laterally from the curb plate. The gate shifting ring 23 is adapted

to be operated in a well known manner so as to simultaneously rotate the wicket gates, and for this purpose said ring has fixed thereto one end of an operating rod 25, the other end of said rod being connected to a governor or actuator (not shown).

One end of each wicket gate 17 is operatively connected with the gate shifting ring 23 by means of a link 26.

As shown in Figs. 3 and 4, one end of the link 26 is formed with an opening 27 through which is inserted a bolt 28 which is also inserted through an opening 29 formed in the gate shifting ring 23. The openings 27 and 29 have different diameters, and the shank of the bolt 28 is likewise correspondingly formed with two diameters, with a shoulder 30 therebetween. The upper end of the bolt 28 is formed with a head 31 which prevents dislodgement of the link 26, and the opposite end of the bolt is threaded for the reception of a nut 32, which retains the bolt in position in the gate shifting ring 23. When the nut 32 is screwed up tight, the shoulder 30, and not the head 31 of the bolt, will be drawn down, thus permitting free swinging movements of the link 26 with respect to the gate shifting ring 23.

The other end 36 of the link 26 is disposed in a notched or cut-out portion 33 in the lower corner of the wicket gate 17, as shown best in Fig. 2.

30 The end 36 of link 26 is formed with an opening 34 having a slot 35 cut into one side.

For the purpose of securing the end 36 of link 26 to the wicket gate 17, I employ a screw 37 having a threaded portion at its upper end disposed in a threaded opening 38 formed in the wicket gate 17, said screw having its main unthreaded portion formed with diametrically disposed parallel plain surfaces 39 which are spaced apart a distance less than the opening of slot 35 so that when the parts are so positioned, the end 36 of the link 26 can be manipulated to engage said screw or to be disengaged from the screw 37.

The opening 34 in the end 36 of the link 26 is formed circular for accommodating the circular portion 41 of screw 37 and permitting free movement of the end of the wicket gate 17 with respect to the link 26 in the usual manner.

In order that the end 36 of the link will be supported from the wicket gate 17, the lower end of the screw 37 is formed with a head 40, as shown in Figs. 4 and 5, and said head is disposed in a suitable cavity 42 in the bottom of the end 36 of the link.

55 When it is desired to remove a link 26 from the turbine, bolt 28 is first removed from the gate shifting ring 23, thereby freeing one end of the link so that said link may be rotated or swung about the screw 37.

60 The link 26 is next moved to the position shown in Fig. 3 by the broken lines A. This action aligns the opening of the slot 35 with the reduced portion of the screw formed by the parallel plain surfaces 39. With the parts thus positioned, the link 26 can now be detached from the wicket gate 17 by moving the link towards the position shown by the broken lines B, Fig. 3.

On the other hand, when it is desired to replace a link, the above operation is reversed, that is to say, a link is first moved from the position shown by the dotted lines B, Fig. 3 to the dotted line position A and then swung around to the full line position. The bolt 28 is then inserted through aligned openings 27 and 29 and the nut 32 applied to the lower end of the bolt.

From the foregoing it will be noted that the screw 37 can remain in position on the underside of the wicket gate, since it is not necessary to remove said screw in order to attach or detach a link 26. Therefore, in order to retain the screw 37 in position in the wicket gate with its plain parallel surfaces 39 properly disposed to permit attachment and detachment of a link 26 in the above described manner, a pin 43 is driven through the screw, as shown in Fig. 4. When it is desired to remove the screw 37, pin 43 can first be removed thereby permitting turning of the screw by means of a suitable tool such as a wrench or the like.

By the present invention, the operation of removal or replacement of the links used with the submerged type of gate operating mechanism with a gate shifting ring on the bottom plate, is considerably facilitated, as will be understood.

Having thus described my invention what I claim is:—

1. In a hydraulic machine, the combination 30 with a gate shifting ring and a pivotally mounted gate adapted to be turned by said ring, of a link, a bolt pivotally connecting one end of said link with said ring, the other end of said link having a slotted opening formed therein, and a member 35 carried by said gate and having a pair of parallel plain surfaces adapted to receive the slotted end of said link when said link is detached from the ring and disposed in one position, said member in all other positions of the link being adapted to 40 provide means for pivotally connecting the slotted end of said link with said gate whereby the gate may be turned by the link from said ring when the opposite end of said link is pivotally connected to said ring.

2. The combination with a gate shifting ring and a pivotally mounted gate adapted to be turned by said ring, of a link, a bolt pivotally connecting one end of said link with said ring, the other end of said link having a slotted opening formed therein, a screw mounted in said gate and having a round shank formed with a pair of parallel plain surfaces spaced apart a distance less than the thickness of the shank, said shank being adapted to receive the slotted end of said link when said link is disposed in one position and detached from said ring, said screw in all other positions of the link being adapted to provide means for pivotally connecting the slotted end of said link with said gate whereby the gate may 50 be turned by the link from said ring, and detachable means for pivotally connecting the opposite end of said link with said ring.

ARTHUR YOUNG. 65
